**MACHINE FOR REMOVING CARTONS
FROM PACKAGES**

Andrew W. Anderson, West Caldwell, N.J., assignor to
Scandia Packaging Machinery Company, North Arling-
ton, N.J., a corporation of New Jersey

Filed July 11, 1963, Ser. No. 294,313
7 Claims. (Cl. 214—310)

This invention relates to a method of and a machine or apparatus for removing cartons from packages enclosed therein.

Packages such as cigarette packages are packed in cartons for sale. However, they are assembled in groups and placed in the cartons. It is sometimes desired to take them out of the cartons and sell them in smaller groups.

After the packages have been placed in the cartons they fit tightly and it is difficult to empty the cartons as friction between the packages and between the packages and the walls of the carton and suction in the carton behind the packages hold the packages tightly in place.

This invention has for its salient object to provide a simple and practical machine or apparatus for easily and quickly emptying a carton of the packages enclosed therein.

Another object of the invention is to provide a simple, practical and efficient method of removing packages from a carton.

Further objects of the invention will appear from the following specification taken in connection with the drawings which form part of this application and in which—

FIG. 1 is a front elevation of a machine constructed in accordance with the invention;

FIG. 2 is a vertical sectional elevation taken substantially on line 2—2 of FIG. 1 looking in the direction of the arrows;

FIG. 3 is a top plan view of the machine shown in FIG. 1;

FIG. 4 is a view similar to FIG. 1 but showing a package in position on the support with the package-engaging means in raised position;

FIG. 5 is a view similar to FIG. 4 showing the position of the parts when a new carton has reached its forward position;

FIG. 6 is a top plan view similar to FIG. 3, the parts being in the position reached after the carton has been removed from the packages;

FIG. 7 is a view similar to FIG. 6 at a later stage of the operation of the machine as will be hereinafter described;

FIG. 8 is a cross-sectional view through the package support showing the carton thereon prior to removal from the packages;

FIG. 9 is a view similar to FIG. 8 but showing the carton and the packages with the package holding suction cups in forward position in engagement with the packages; and

FIG. 10 is a perspective elevational view of the carton with the closing flaps open.

The invention briefly described comprises means for supporting and feeding a loaded package with the closing flaps open, means for engaging and holding the packages, and means for blowing the cartons away from the packages enclosed therein by air blasts directed above and below the packages in the carton.

In the particular embodiment of the invention illustrated in the drawings the apparatus or machine comprises a table or supporting surface 20 above which is mounted a feed chain 21 having a feeding lug 22 which engages the carton placed on the table or support and feeds the cartons forwardly to a position indicated at A.

The chain 21 is rotatably mounted on a sprocket 23,

2

on a shaft 24, on a sprocket 25, and on a shaft 26. The shaft 26 is driven by a belt and pulley connection from a shaft 27 of a motor M. The shaft 24 is driven as shown in FIG. 3 by a sprocket and chain connection from shaft 26.

Package holding means

When the loaded package of cigarettes reaches the position shown at A in FIGS. 4 and 7 two operations are carried out, namely, means is moved into operating position to engage the outer ends of the packages to hold them against movement and after this holding means has come into operation means in the form of air blasts are directed inside the cartons above and below the cigarette packages to remove the carton from the cigarette packages which are being held. This is accomplished in the following manner.

Before the holding means comes into operation it is necessary that the loaded cartons be accurately positioned in the position indicated at A. It is also necessary that the carton be effectively backed up or held against lateral movement on the platform when the package holding means come into operation. The carton is backed up in this manner by a plate 30 which is mounted at the upper end of a slotted bar 31 which in turn is supported on a stud 32 and a shaft 33. The bar 31 has a roller 34 which engages a cam 35. The bar 31 is held downwardly by a spring 36 which holds the roller 34 against the cam 35.

The cam 35 is so designed as to hold the plate 30 in its lower position when the roller is in engagement with the portion 38 of the cam and to hold the plate in its elevated position when the roller 34 engages the portion 37 of the cam surface.

After the carton has been fed to the position A a stop means is provided to determine its forward movement and this stop means consists of a lug 40 which is momentarily positioned in the path of movement of the carton by reason of the portion 41 of cam 35 in engagement with the roller 34 on the bar 31. The operating position of the portion 41 of the cam 35 is shown in FIG. 5.

When the package has reached the position A it will be disposed opposite a bar 50 which is mounted on the top of plate 51. The plate 51 has a bushing 52 slidably mounted on a shaft 53 on which is mounted a cam 54 engageable with a roller 55 carried by the bushing 52. The shaft 53 is driven by a chain 56 from the shaft 26. As the shaft 53 is thus rotated the cam 54 will act on the roller 55 carried by the bushing 52 and move the plate 51 and bar 50 into operating position. The plate is also engaged by a spring 58 which forces the plate 51 and block 50 to the right or to retracted position after it has been moved forward by the cam 54.

The block 50 has mounted thereon a plurality of suction cups 60 which communicate with the suction conduits 62 inside the block and these conduits are connected to a conduit 63 which connects at its other end to a suction chamber 64. The chamber 64 has a plunger valve 65 which is controlled by a lever 66 pivoted at 67 to a bracket 68 mounted on the chamber 64. The lever 66 carries a roller 70 which engages a cam 71 mounted on the shaft 24. As the cam is rotated the lever will be moved to open and close the valve 65 and thus connect the suction cups 60 to the suction chamber 64.

The sequence of operations is so timed that the block 50 will be moved forward to operating position when the carton has been positioned at the position A and the plate 30 has been raised by the cam 35 to the position shown in FIGS. 4 and 5. The shaft 33 which rotates the cam 35 is connected to the shaft 26 by a chain 69. As soon as the block 50 has been moved to its forward position shown in FIG. 9 the plate 30 is lowered by the operation of cam 35 to the position shown in FIG. 1.

When the holding operation has been made effective and the packages are held by the suction connected to the suction cups 60, the carton is blown off from the packages or removed from the packages by air blasts in the following manner.

Carton blasting means

The block 50 in addition to housing the suction conduits for the suction cups 60 also has air blast conduits 75 and 76 which lead to a plurality of conduits 77 and 78 which as shown in FIG. 9 diverge away from each other and lead to outlet openings 79 at the bottom block and to outlet openings 80 at the top of the block 50. The conduits 75 in the block are supplied with air under pressure by a conduit 81 which leads to an air chamber 82 having a valve 83 controlled by a lever 84 pivoted at 85 to a bracket 86 on the air chamber 82. The lever 84 has a roller 87 which engages a cam 88 mounted on a shaft 24.

After the carton has been moved to position A on the platform 20 opposite the block 50 and the packages in the carton have been engaged by the suction cups and held in position the plate 30 is moved to depress position as shown in FIG. 1 and air from the air chamber 82 will be released through the valve 83 to the conduit 81 and will be directed through the divergent conduits 77 and 78 into the carton beneath the upper wall 90 and above the lower wall of the carton 92. As the air blast enters the carton it will relieve the friction between the packages and the lower and upper walls thereof and will also pass in back of the packages thus exerting pressure in back of the packages and blowing the carton from the packages which are being held by the suction cups.

It will be understood that the various cams are so designed as to function effectively to move the block 50 into operating position and to control the position of the plate 30 and control the suction and air blast valves to eject the air and remove the carton from the packages as they are held by the suction cups.

Although one specific embodiment of the invention has been illustrated and described it will be understood that the invention is capable of modification and that changes in the structure and arrangement of the various parts may be made without departing from the spirit and scope of the invention as expressed in the following claims.

I claim:

1. Apparatus for removing cartons from a plurality of packages enclosed therein comprising means for supporting the loaded cartons, suction means above the support for holding the individual packages and means operable, while the packages are being held, for directing air blasts into the carton above and below the packages therein for flexing the upper and lower walls of the carton and freeing them from frictional contact with the packages for more effectively blowing the cartons away from the packages.

2. Apparatus for removing cartons from a plurality of packages enclosed therein comprising means for supporting the loaded cartons, means for feeding the loaded cartons on the support, removable means for stopping the cartons in a predetermined position, suction means above the support for engaging and holding the individual packages and means operable, while the packages are being held, for flexing the upper and lower walls of the carton and freeing them from frictional contact with the packages for more effectively blowing the cartons away from the packages.

3. Apparatus for removing packages from cartons comprising a support for the cartons of packages, means to feed the cartons along the support, suction conduits disposed above and along the back edge of the path of travel of the cartons, and air blast conduits disposed along the back edge of the path of travel of the cartons and spaced to direct air blasts below and above packages in the carton for flexing the upper and lower walls of the carton and freeing them from frictional contact with the packages

for more effectively blowing the carton away from the packages, said suction conduits being connected to a source of suction and said air blast conduits being connected to a source of air pressure.

5. Apparatus for removing packages from a carton comprising a support for cartons of packages, suction cups disposed above the support engageable with the individual packages in the carton, air blast conduits disposed above the support for flexing the upper and lower walls of the carton and freeing them from frictional contact with the packages for more effectively blowing the cartons away from the packages, and means for moving the suction cups and air blast conduits transversely toward and away from the path of travel of the cartons on the support.

10 5. Apparatus for removing packages from a carton comprising a support for cartons of packages, suction cups disposed above the support, air blast conduits disposed above the support for flexing the upper and lower walls of the carton and freeing them from frictional contact with the packages for more effectively blowing the cartons away from the packages, means for moving the suction cups and air blast conduits transversely toward the path of travel of a carton on the support when a carton reaches a predetermined position on the support, and means for connecting the suction cups to a source of suction when the cups have been moved toward the carton and packages.

15 6. Apparatus for removing packages from a carton comprising a support for cartons of packages, suction cups disposed above the support, air blast conduits disposed above the support, means for moving the suction cups and air blast conduits transversely toward the path of travel of a carton on the support when a carton reaches a predetermined position on the support, means for connecting the suction cups to a source of suction when the cups have been moved toward the carton and packages and means for connecting the air conduits to a source of compressed air when the air blast conduits have been moved toward the carton and packages and in a position to direct blasts of air between the upper and lower walls 20 of the carton and packages contained therein for flexing said upper and lower walls and freeing them from frictional contact with the packages for more effectively blowing the cartons away from the packages.

25 7. Apparatus for removing packages from a carton comprising a support for cartons of packages, suction cups disposed above and to one side of the support, air blast conduits disposed above on said one side of said support, means for moving the suction cups and air blast conduits transversely toward the path of travel of a carton on the support when a carton reaches a predetermined position on the support, a backing plate disposed on the other side of the support and at the outer edge of the path of travel of the cartons and means for raising the plate above the support when a carton reaches a predetermined position 30 on the support and the suction cups are moved into operative position in engagement with the packages, means to apply suction to said packages in the last mentioned position, said means for raising the plate being then operated to the lower plate, means for delivering air to said air blast conduits while the plate is lowered to thereby blow away the carton across the area formerly occupied by the plate while the suction cups are secured to the packages.
